(57) **CLAIM**

The ornamental design for a face mask, as shown and described.

DESCRIPTION

FIG. 1 is a perspective view of a face mask showing our new design.

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective view of the face mask in a condition of use.

The portions of the face mask in FIGS. 1–8 shown in broken lines are intended to show features that form no part of the claimed design. The dot dash broken lines illustrate the boundary of the claim and form no part of the claimed design.

1 Claim, 4 Drawing Sheets
